(57) **CLAIM**

The ornamental design for a cosmetic container, as shown and described.

DESCRIPTION

FIG. 1 is a perspective view of a cosmetic container showing my new design;

FIG. 2 is a front elevational view thereof where a rear elevational view thereof is identical to the front elevational view of FIG. 2;

FIG. 3 is a left side view thereof where a right side view thereof is identical to the left side view of FIG. 3;

FIG. 4 is a top plan view thereof;

FIG. 5 is a bottom plan view thereof;

FIG. 6 is a cross-sectional view thereof, taken along line 6-6 in FIG. 4;

FIG. 7 is a perspective view thereof shown in an open position with top and bottom lids removed;

FIG. 8 is a front elevational view thereof shown in FIG. 7;

FIG. 9 is a rear elevational view thereof shown in FIG. 7;

FIG. 10 is a left side view thereof shown in FIG. 7;

FIG. 11 is a right side view thereof shown in FIG. 7;

FIG. 12 is a top plan view thereof shown in FIG. 7;

FIG. 13 is a bottom side view thereof shown in FIG. 7; and,

FIG. 14 is an exploded view thereof.

In the drawings, the broken lines are for the purpose of illustrating portions of the cosmetic container that form no part of the claimed design.
